UNITED STATES PATENT OFFICE.

ANDREW E. WESTBERG, OF FIVE CREEKS TOWNSHIP, CLAY COUNTY, KANSAS.

LARIAT-NOOSE CLIP.

1,075,179.

Specification of Letters Patent.

Patented Oct. 7, 1913.

Application filed August 28, 1912. Serial No. 717,463.

To all whom it may concern:

Be it known that I, ANDREW E. WESTBERG, a citizen of the United States, residing in Five Creeks township, in the county of Clay and State of Kansas, have invented certain new and useful Improvements in Lariat-Noose Clips, of which the following is a specification.

My invention relates to devices for releasing animals from a hitching strap or rope and is especially adapted to use with a lariat or halter when, by reason of the struggling of the animal or for other cause, the rope or halter has been drawn extremely taut.

15 The objects are to provide a simple, light, readily applied and easily released clip, the construction of which will be more readily understood by reference to the following description and accompanying drawings, in

20 which—

Figure 1 is a perspective view of my device with a portion of the casing removed, exposing the locking mechanism in process of opening. Fig. 2 is a detail perspective view illustrating one of the clip jaws in disassembled relation. Fig. 3 is a front elevation with parts of the clip jaws broken away to clearly disclose the assembled relation of the parts when in locked position and Fig. 4 a

25 detail view of side 2.

Similar numerals indicate like parts throughout the several views.

The openings 4 are merely to reduce the weight where they will not sacrifice required strength. For the purpose of increasing strength where required, the jaws are made thicker at 5. The end A of the halter or rope is passed through the openings 3 and secured to the body of the rope, thus forming a hinge at that end of the clip. Within the jaw of the side 1 is pivoted, at 7, the lever 6 and within the jaw of the side 2 is

pivoted, at 9, a clamp 8. The rod 11, across the interior of 1, carries the spring 10 which serves to hold the clamp 8 in position when the device is locked, the spring being curved at 13 in such a manner as to bear against the under side of the curve 14 when the clip is closed. The block 12 is merely for the purpose of keeping the clamp 8 from dropping below the position of engagement with the opposite jaw when the clamp is disengaged.

To operate my device;—the same is closed by pressing the jaws together, the clamp 8 engaging the flange 13 of the lever 6 and the spring 10 forcing the clamp tightly against such lever holds them in an approximately horizontal position, thus securely locking the clip. To release the same, the lever 6 is raised till, by the engagement with the clamp 8, it has thrown the same free, allowing the jaws to separate.

Having thus described my invention what I claim as new and desire to secure by Letters Patent is,—

The combination with a lariat, of a noose clip adapted to be attached to the noosed end thereof, said clip including a pair of clip jaws, each of said jaws being provided with a terminal aperture, said aperture being adapted to receive the terminal of said lariat, a hook-shaped pawl pivoted to the first of said jaws, a locking dog pivotally attached to the second of said jaws and adapted to coöperate with said pawl in locking said clip jaws in closed position, and a spring carried by the second of said clip jaws for normally holding said pawl and dog in locking relation.

ANDREW E. WESTBERG.
